UNITED STATES PATENT OFFICE.

LEVI J. ODELL, OF LOS ANGELES, CALIFORNIA.

RAZOR-SHARPENING MACHINE.

1,111,316.

Specification of Letters Patent. Patented Sept. 22, 1914.

Application filed February 3, 1913. Serial No. 745,764.

To all whom it may concern:

Be it known that I, LEVI J. ODELL, a citizen of the United States, residing at Los Angeles, in the county of Los Angeles and State of California, have invented new and useful Improvements in Razor-Sharpening Machines, of which the following is a specification.

This invention relates to improvements in machines for stropping razor blades and particularly to that class of blades commonly called "wafer" blades, commonly used in safety razors, and the principal object of the invention is to provide a machine 10 provided with a battery of blade holders and to alternately bring the blades in contact with a pair of revolving stropping rolls, and reciprocate the blades in relation to the abrading periphery of the rolls.

It is a further object to provide a frame 20 for the battery of blade holders which is oscillated and reciprocated automatically by means of the same cam.

In the drawings Figure 1 is a plan view 25 of the machine, a portion of one of the rolls being broken away, together with the top bar of the frame, to clearly show the position of the blade holders in relation to the rolls. Fig. 2 is a front elevation of the machine, a portion of the cam drive shaft being broken away to clearly show the adjustable connecting rod. Fig. 3 is an end view of the upper part of the table, together with the abrading roller and the blade holder carrying frame, a portion of the drive pulley on this end being broken away to clearly show the pivotal means for the blade carrying frame. Fig. 4 is a section on the line 4-4 of Fig. 2, viewed in the direction indicated by 40 the arrows.

In the drawings, the component parts are indicated by numerals, 6 being the top of the table, supported by means of legs 7, the driving mechanism being located preferably 45 below the table and not shown in the drawings. The frame work supported on the table being preferably castings formed by side and top pieces, the sides or ends 8 and 9 consisting of L shaped pieces provided with a horizontal portion which rests upon the top of the table and is secured to lugs 10, preferably formed integrally with the table top, by means of suitable fastenings, as the screws 11, the two lugs being placed at a 50 proper distance to accommodate the end pieces which are provided with a plurality

of bearings. Two of these bearings 12 and 14 in end piece 8 are placed vertically one above the other in the vertical limb of the piece, the other bearing 15 being located in an extension of the horizontal portion and slightly below the horizontal plane of the bearing 14. The opposite end piece 9 is provided with bearings in a line with these latter and designated 16, 17 and 18 respectively. A top bar 20 joins the tops of the end pieces to form a complete frame for the abrading rolls, the top piece 20 being preferably of such width as to provide a certain amount of protection or shield to the upper 70 roll.

Mounted in the bearings 12 and 16 is a shaft 21 on which is securely mounted the roll 22, provided with an abrading surface 23 of suitable material, usually and preferably of leather, the end of the shaft adjacent bearing 16 having secured thereon the pulley 24.

Revolutely mounted in the bearings 14 and 17 is the shaft 25, on which is secured 80 the roll 26 with a suitable abrading surface 27, this shaft being extended beyond the bearing 14 and has secured thereon the pulley wheel 28. Suitable belts, not shown, are connected to these pulleys from a main 35 drive shaft below the table, to drive them in the direction indicated by the arrows in Figs. 3 and 4, an interval being interposed between the adjacent portions of the abrading peripheries to provide for the contact 90 of the blades therewith.

Mounted in the bearings 15 and 18 and adapted to rotate therein, is the shaft 30, the end of this shaft being preferably carried beyond the bearing 18 and provided 105 with a pulley wheel 31, a suitable belt being connected with this pulley to drive the shaft in a direction opposite to that of the lower abrading roll, as illustrated by the arrow, and at the proper speed from the main 110 drive shaft below the table top.

On the shaft 30 and adjacent the bearing 18 is mounted the cam wheel 32 which consists, preferably of a cylindrical sleeve provided with the cam flanges 34, which extend outwardly and are so formed as to complete a continuous worm channel, with two flattened portions, in which a plurality of cam rollers engage and are positively operated, there being just sufficient play to permit of 115 the revolution of the cam rollers.

Extending from the end pieces inwardly or

toward the bearings of the cam-shaft, are the lugs 35 and 36, formed similarly on each end piece and in the same plane, a vertical bore being carried through these extensions, in 5 which is secured the shaft 37.

Embracing the shaft and being pivotally mounted thereon, are the brackets 38, the ends of the brackets engaging with the shaft being preferably a yoke having the bearing 10 extensions which engage with the inner faces of the extensions 35 and 36 so as to provide support therefor and are pivotally mounted on this shaft. These brackets are of sufficient length to extend over and above the 15 vertical plane of the cam shaft and are provided with bearings 39 in this plane, which are pivotally mounted by means of the trunnions 40 in bearings 41 formed on the oppositely disposed upper and lower sides of 20 the ring 42 formed in this front end of the bracket.

Mounted in the bearings 39 are the trunnions 43 formed on the oppositely disposed ends of the casting 44, forming the support 25 or holder for the battery of blade holding devices, this casting being somewhat in the form of a yoke, the parts being so disposed that the axes of the trunnions are preferably in the same line with the axes of the 30 trunnions on the blade holders which are pivotally mounted on the frame. This blade holder frame is provided with a floor 45 on which are formed the plurality of vertical studs 46, intermediate of which are secured 35 the blade holder brackets 47, these latter, as shown, being formed as short channels with vertical sides 48, which are notched to receive the trunnions of the blade holders which, as shown, are of similar construction 40 to those disclosed in my United States Patent No. 1,051,817, for razor sharpening machines, dated January 28, 1913. The supporting frames, however, shown, are provided with the guide bars 49 placed on 45 either side of the front of said brackets, so that the shank 50 of the blade holder is positively guided in a vertical direction and the trunnions 51 are relieved of considerable strain incident to the reciprocation of the 50 blade holder frame and the blade in relation to the abrading rolls.

The studs 46 previously referred to, act as sockets, within which are secured the threaded ends of the screw clamp 52, by 55 which the yoke ends of the spring or resilient blades 53, secured to the shank of the blade-holder 50, are locked to hold the blade holder in operative position on the frame.

On the lower face of the blade holder 60 frame is formed the stud 54 which is provided with the stub shaft on which is mounted the roller 55, this roller being so disposed that it engages in the worm channel formed by the flanges 34, the movement 65 being such that a complete revolution of the

cam worm reciprocates the blade holder and the blades in a plane parallel to the plane carried through the axes of the abrading rolls a distance slightly greater than the space between adjacent blade jaws, and the 70 blade held there-between so that the entire periphery of the abrading roll is engaged by the blade and the wearing of channels in the surfaces is eliminated.

To provide the oscillating movement, two 75 lugs 56 and 57 are formed also on the lower face of the blade holder frame, and provided with a bore therethrough parallel with the upper face forming the floor in which is pivotally mounted a shaft 58 formed as 80 an extension of the shank 59, which is provided with a trunnion 60, this trunnion being engaged by the arms 61 of the yoke 62.

The lower end of the yoke is provided with a threaded bore in which is inserted 85 the upper portion 63 of the reversely threaded screw 64, the lower end of this screw being carried through a threaded bore in the extension 65, which is pivotally mounted in the yoke 66 by means of the trunnion 67. The arms of the yoke 66 embrace and are pivoted by means of the pin 68 to a lower arm 69 of the bell crank lever, which is provided with a vertically disposed arm 70, the upper end of the arm being provided with a 90 short shaft with its axis in the same plane as the horizontal axial plane of the cam shaft on which is mounted the roller 71, which roller is preferably of the same diameter as the roller 55 and engages in the worm channel 95 formed by the cam flanges 34, a revolution of the worm reciprocating the arm 70 of the bell crank, which movement is transmitted through the adjustable connections described and oscillates the blade holder frame to press the blade alternately against the upper and the lower abrading rolls.

The operation of the device will be readily understood by the above description, suitable motive power being applied by 110 belts, as previously described, to the various pulleys thereby revolving the shafts in the directions indicated. The rotation of the shaft 30 and the cam 32 operates to cause the latter to act to effect alternate vertical rocking and longitudinal reciprocal movement of the blade-carrying frame; the frame being first rocked vertically to move the blade or blades carried thereby into contact with one of the rolls 22 or 26. The moment the blade contacts the roll the frame will be given a longitudinal reciprocal movement by the cam 22 to move the blade substantially parallel with the surface of the abrading roll a distance approximating the width of the space between adjacent blades so that the wear of the abrading surfaces will be 120 equalized throughout said surfaces by the movement of the blades over the entire periphery of the rolls, thus preventing the for- 125 130

mation of channels thereon and insuring an even grinding of the blades.

What I claim is:

1. In a razor blade sharpening machine, 5 a pair of spaced stropping rolls, a frame mounted to rock vertically and to reciprocate longitudinally substantially parallel with said rolls, means for supporting a plurality of blades on said frame, a cam, and 10 separately operated means whereby the rotation of said cam will operate to effect alternate rocking and reciprocating movement of said frame.
2. In a razor stropping machine a pair of 15 cylindrical stropping rolls, a frame extending parallel with said rolls, and pivoted to rock vertically, a swinging support for the pivotal bearings of said frame by which said frame can be shifted longitudinally, a 20 plurality of blade-carriers on said frame adapted to position a series of blades intermediate said rolls, a cam shaft, a single grooved cam on said shaft, and separately 25 actuated means whereby the rotation of said cam will operate to effect alternate rocking and reciprocating movement of said frame in both directions.
3. In a razor stropping machine a pair of 30 cylindrical stropping rolls, a blade carrying frame extending parallel with said rolls, a pair of horizontally swinging arms adjacent the ends of said rolls on which said

frame is pivotally mounted to rock vertically, a cam shaft, a single cam on said shaft, and separately actuated means engaged by said cam, whereby the frame will be caused to alternately rock vertically and reciprocate longitudinally. 35

4. In a razor stropping machine the combination with a pair of spaced cylindrical 40 stropping rolls, a frame carrying a plurality of blade holders adapted to position the blades intermediate said stropping rolls, trunnions on the ends of said frame, bearings in which said trunnions are turnably 45 mounted, a pair of arms pivoted to swing horizontally on which said bearings are pivoted, a single peripherally grooved cam, and connections whereby the rotation of said cam will operate to rock said frame vertically to move the blades into alternate contact with said rolls, and whereby the frame will be moved longitudinally on said arms to reciprocate the blades in both directions 50 when in contact with said rolls and longitudinally thereof. 55

In witness that I claim the foregoing I have hereunto subscribed my name this 24th day of January, 1918.
